UNITED STATES PATENT OFFICE

170,435

SPECTACLE FRONT

Harry Weissman, New Hyde Park, N. Y.

Application July 21, 1952, Serial No. 20,706

Term of patent 14 years

(Cl. D57—1)

To all whom it may concern:

Be it known that I, Harry Weissman, a citizen of the United States and resident of New Hyde Park, in the county of Nassau and State of New York, have invented a new, original, and ornamental Design for a Spectacle Front, of which the following is a specification, reference being had to the accompanying drawing forming part hereof.

Fig. 1 is a top plan view of a spectacle front, showing my new design.

Fig. 2 is a front elevational view thereof.

Fig. 3 is a fragmentary rear elevational view, on an enlarged scale, of the nose bridge portion of the spectacle front.

Fig. 4 is a top plan view of that portion of the spectacle front shown in Fig. 3.

Fig. 5 is a vertical sectional view of that portion of the spectacle front shown in Fig. 3, said view being taken on the line 5—5 of Fig. 3.

The dominant features of the design reside in the portions shown in full lines.

I claim:

The ornamental design for a spectacle front, substantially as shown and described.

HARRY WEISSMAN.
